UNITED STATES PATENT OFFICE.

CHARLES F. OSGOOD, OF CLAREMONT, NEW HAMPSHIRE, ASSIGNOR TO SULLIVAN MACHINERY COMPANY, A CORPORATION OF MASSACHUSETTS.

FURNACE.

Application filed March 11, 1925. Serial No. 14,770.

My invention relates to furnaces.

An object of my invention is to provide an improved furnace. Another object of my invention is to provide an improved blank heating furnace for heating blanks preliminary to forging operations. A further object of my invention is to provide an improved heating furnace having means whereby blanks may be automatically fed through the furnace and automatically discharged when heated to the desired temperature. Still another object of my invention is to provide an improved blank heating furnace having improved means whereby the discharge of the blanks from the furnace may be controlled automatically in accordance with the temperature therein. Another object of my invention is to provide a blank heating furnace having automatically driven reciprocable blank discharge mechanism wherein said discharge mechanism may be controlled automatically in accordance with the variation of the temperature in the furnace. A still further object of my invention is to provide an improved automatic blank heating furnace wherein the maximum heating efficiency and a uniform temperature of the blanks may be obtained. These and other objects and advantages of my invention will, however, hereinafter more fully appear.

In the accompanying drawings I have shown for purposes of illustration one form which my invention may assume in practice.

In these drawings,—

Fig. 1 is a vertical sectional view through my improved blank heating furnace, certain parts thereof being shown in elevation.

Fig. 2 is a vertical transverse sectional view taken substantially on line 2—2 of Fig. 1.

Fig. 3 is a diagrammatic view of my improved controlling mechanism.

In this illustrative construction I have shown a blank heating furnace, generally designated 1, of the same general type as that described in a pending application to one Sven T. Nelson, Serial No. 511,900, filed October 31, 1921 with the exception of differences and improvements pointed out below, and including automatic blank discharging means, generally designated 2. The furnace 1 together with the blank discharging means 2 is mounted upon a suitable frame or casing 3 of generally rectangular cross section having the usual supporting legs 4 and a substantially horizontal metal cover or housing 5 at the top thereof. The frame 3 and

the cover 5 are lined on the top, bottom, sides, and back with fire brick 6, all joints being luted with fire clay. Carried by the cover member 5 there is an oil burner 7 of usual form having an atomizing nozzle 8 projecting downwardly through a suitable opening 9 formed in the fire brick. This burner 7 is disposed in a substantially vertical plane and is adapted to discharge a gaseous mixture directly toward the inclined bottom of a combustion chamber 10. The combustion chamber 10 is provided with inclined sides and front walls 11 and a vertical rear wall 12 which converge toward the bottom of the furnace, restricting the same and thereby intensifying the heat at that point. Suitable laterally disposed vents or flues 13 are provided contiguous to the bottom of the chamber for discharging the burned gaseous mixture from the combustion chamber.

Disposed centrally of the inclined front wall of the furnace and projecting within the combustion chamber 10 are guide ribs 14 providing an inclined guideway for a series of blanks 15. Arranged in the cover member 5 at the top of the furnace is a feed slot 16 provided with a pivoted closure member 17 and this slot is disposed in alignment with the channel formed by the guide ribs 14 in which the blanks are to be guided during heating thereof. It will herein be observed that the blanks inserted through the slot 16 remain superimposed, one upon another, between the guides 14 and are gradually fed down on operation of improved discharging means to be hereinafter described by gravity. It will be evident that the blanks may be fed into the furnace in any other suitable manner. It will also be evident that one or more stacks of bits may be provided in the furnace and that the furnace may be designed to accommodate as many stacks as desired. Herein it will be noted from Figs. 1 and 2 that the blanks are partially protected by the guides 14 from the direct heat of the combustion chamber and as a result, only the projecting portion, which will be the portion to be worked, will be heated up to the highest temperature.

The bottom of the furnace is provided with a suitable water jacket 18 of usual form and at the upper surface of the water jacket in the bottom plate of the furnace there is formed a guideway 19 in which a plunger or ejector 20 is reciprocable adapted to engage

2

the bottom blank in the stack and force the blank out through a downwardly inclined discharge opening 21. The rear end of the ejector 20 is pivotally connected, as at 22, to a suitable crosshead member 23, slideable in inclined guideways 24 formed within a supporting bracket 25 suitably secured to the frame 3. Pivotally connected, as at 26, to the crosshead and to a crank disk 27 is a connecting rod or pitman 28. The crank disk 27 is suitably secured to a horizontal shaft 29 through suitable reduction gearing 30 and 31 from an electric motor 32 which is herein of the variable speed type. It is obvious that suitable worm gearing, compound spur gearing or reduction gearing of any other suitable type could be substituted for the reduction gearing shown. It will herein be noted that the water jacket 18 prevents excessive heating 10 of the ejector 20. It will also be evident that the guides 14 may be water cooled if desired. Improved controlling means are provided for the motor 32 whereby the speed of the latter may be controlled automatically in accordance with the temperature in the furnace. Such means comprises a thermo-couple 33 which projects laterally into the furnace at a point in front of the stack of blanks and away from the direct flame of the burner as clearly 20 illustrated in Fig. 1. However, if desired the thermo-couple may be located at other points in the furnace. This thermo-couple is of well known commercial form and includes means for generating, by means of the heat of the furnace, low voltage electricity. As shown, the thermo-couple 33 is connected by means of conducting wires 34 with a control pyrometer, generally designated 35, which is herein of a well known commercial type and specifically does not enter into my invention. The pyrometer is connected through conductors 36 with the main supply lines 37 and this pyrometer is adapted to control the flow of current from the main line wires 37 through conductor wires 38 leading to a controlling mechanism, generally designated 39, which is of well known commercial type and further description of the same is believed unnecessary save that it preferably includes an electrically driven servo-motor (not shown) which is adapted to actuate, through suitable connections including a link 40, a lever 41 of a rheostat 42 or other suitable controlling device, the latter of which is adapted to control the flow of current from the main supply lines 37 through conductor wires 43 leading to the motor 32 in a well known manner. It will herein be noted that in place of a servo-motor any suitable type of control relay switch mechanism, a solenoid device, or the like may be used to cut in or cut out the motor circuit as is well known in the art.

In the operation of my improved furnace above described, it will herein be noted that 60 after the stack of blanks have been inserted

into the furnace through the slot 16 and the burner 7 has been regulated, bringing the temperature within the combustion chamber to approximately the desired maximum, heat is absorbed by the blanks and is transmitted to the thermo-couple 33. Electricity is generated within the thermo-couple and is transmitted through the conductor 34 to the control pyrometer 35 which controls the flow of current from the conductor 36 through the conductor 38 to the controlling mechanism 39, actuating the latter and consequently through the connections 40 the rheostat lever is swung about its pivot, thus connecting the conductor 43 with the main line 37 and actuating the discharge motor 32. The motor 32 then actuates, through the connections heretofore described, the plunger 20 and the blanks being intermittently discharged from the furnace at the requisite speed. As the heat varies within the furnace the flow of current to the motor 32 is consequently varied by means of the controlling devices 35 and 39. It will be evident that when the temperature within the combustion chamber is too low the motor 32 is stopped, consequently stopping the blank discharge mechanism and when the temperature within the combustion chamber increases the speed of the motor 32 is proportionally increased.

As a result of my invention it will herein be noted that an improved blank heating furnace is provided wherein maximum efficiency and a uniform temperature of the discharge blanks is obtained. It will further be noted that an improved furnace is provided wherein as the temperature within the combustion chamber varies, the speed of the blank discharge is also varied, thus eliminating a too hot or a too cold blank.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a blank heating furnace, a vertically elongated combustion chamber having provision at its lower end for the discharge of the products of combustion therefrom, a blank guide extending toward the bottom thereof, and a burner carried by the top of said furnace and discharging downwardly toward the bottom of said chamber, the blanks in said guide moving in the direction of the burner discharge and directly in the path of the flame.

2. In a blank heating furnace, a vertically elongated combustion chamber having provision at its lower end for the discharge of the products of combustion therefrom, an in-

- clined blank guide formed therein, a burner carried by the top of said furnace and discharging toward the bottom thereof, the blanks in said guide moving in the direction 5 of the burner discharge and directly in the path of the flame, and means for discharging the blanks from the bottom of said chamber.
3. In a blank heating furnace, a vertically elongated combustion chamber having means 10 for graduating the heat toward a maximum at the lower end thereof and having provision at its lower end for the discharge of the products of combustion therefrom, a burner discharging toward said lower end, and means 15 for guiding blanks longitudinally of said chamber directly in the path of the burner discharge to discharge said blanks adjacent said hottest end.
4. In a blank heating furnace, a vertically 20 elongated combustion chamber having a relatively narrow portion tending to intensify the heat at the lower end thereof and having adjacent said lower end provision for the discharge of the products of combustion, and a 25 burner carried by the top of said furnace discharging toward said end, and means for conducting blanks relative to said chamber to discharge adjacent said end.
5. In a blank heating furnace, a vertically 30 elongated combustion chamber having provision at its lower end for the discharge of the products of combustion therefrom and provided with a substantially vertical side wall and an inclined side wall to form a narrow portion at one end thereof for intensifying 35 the heat at said end, and means for conveying a series of blanks along said inclined side wall to discharge said blanks adjacent the hottest point in said combustion chamber.
- 40 6. In a blank heating furnace, an elongated substantially vertical combustion chamber having provision at its lower end for the discharge of the products of combustion therefrom and having an inclined bottom and a 45 burner discharging longitudinally therein, and means for conducting a series of blanks longitudinally along said chamber in the direction of the burner discharge.
- 50 7. In a blank heating furnace, a substantially vertical elongated combustion chamber having adjacent its lower end provision for the discharge of the products of combustion and provided with an inclined bottom and a 55 substantially horizontal top, a burner carried by said top, and means for conducting a series of blanks longitudinally of said chamber in the direction of the burner discharge.
- 60 8. In a blank heating furnace, a substantially vertical elongated combustion chamber provided with an inclined bottom and a substantially horizontal top, said combustion chamber having provision adjacent its lower end for the discharge of the combustion products, a burner carried by said top, means 65 for conducting a series of blanks longitudi-

nally of said chamber in the direction of the burner discharge, and means to automatically discharge said blanks at the end of said chamber remote from said burner.

9. In a blank heating furnace, a vertically 70 elongated combustion chamber having means for graduating the heat towards a maximum at the lower end thereof, a burner discharging toward said end, said chamber having provision for the discharge of the products 75 of combustion adjacent its lower end, and means for guiding the blanks through said chamber in the direction of the burner discharge to discharge adjacent said hottest end.

10. In a blank heating furnace, a combustion chamber, a blank guide formed therein, means to feed the blanks through the top of said chamber, means including a reciprocating plunger to eject the blanks from said chamber, and means for automatically regulating the rate of movement of said ejecting means to vary the blank discharge in accordance with variations in combustion chamber temperature.

11. In a blank heating furnace, a vertically 90 elongated combustion chamber, a burner discharging therein in a longitudinal direction thereof, said combustion chamber tapering in the direction of burner discharge and having a relatively restricted bottom for intensifying the heat, and adjacent said bottom provision for the discharge of the products of combustion, and means extending through said chamber for conducting a series of blanks 95 towards the restricted end thereof to discharge.

12. In a blank heating furnace, a vertically 100 elongated heating chamber having converging walls and at the smaller end thereof provision for the discharge of the products of combustion, a burner discharging longitudinally of said chamber generally in a direction of convergence of said walls, and means for guiding a series of blanks longitudinally of said chamber towards the smaller 105 end thereof with only the portions to be worked extending into the path of said burner discharge.

13. In a blank heating furnace, a vertically 110 elongated heating chamber having a relatively narrow lower end and having provision for the discharge of the products of combustion at said lower end, a burner discharging toward said narrow end, and means for guiding a series of blanks through said chamber 115 to discharge adjacent said narrow end.

14. In a blank heating furnace, a vertically 120 elongated tapered heating chamber having blank discharging means adjacent the relatively narrow bottom end thereof and having provision for the discharge of the products of combustion at said bottom end, a burner discharging toward the point of discharge of said blanks, and means to guide a series of blanks 125 longitudinally of said chamber while

subjecting them to continuous heat, and means to discharge the blanks of highest temperature therefrom adjacent said narrow end.

15. In a blank heating furnace, a vertically elongated heating chamber having a relatively restricted portion at its lower end to intensify the heat and having provision for the discharge of the products of combustion at said lower end; a burner discharging toward said restricted portion, and means to guide a series of blanks through said chamber and towards said restricted portion while subjecting them to continuous heat, and means to discharge the blanks of highest temperature from said chamber adjacent said restricted portion.

16. In a blank heating furnace, a combustion chamber, means for supporting a stack of blanks in the furnace in position to be heated, mechanism for discharging the blanks from said furnace, an electric motor for continuously driving said discharge mechanism, and control means responsive to temperature in said combustion chamber for controlling the current flow to said motor.

17. In a blank heating furnace, a combustion chamber, a burner arranged at one end thereof adapted to generate different degrees of heat along said combustion chamber, means for supporting a series of blanks at different points along said combustion chamber in the path of the burner discharge, and means for automatically ejecting said blanks adjacent the hottest point in the furnace, an electric motor for driving said ejecting means continuously at different rates, and means re-

sponsive to temperature in said combustion chamber adjacent the point of blank discharge for controlling the current supply to said motor to control the rate of drive thereby.

18. In a blank heating furnace, a combustion chamber, means for admitting blanks thereto, means for maintaining the interior of said chamber at different substantially uniform high temperatures, and means controlled by the temperature within said chamber for automatically successively discharging blanks therefrom while the temperature therein remains substantially constant.

19. In a blank heating furnace, a combustion chamber, means for admitting blanks thereto, means for discharging blanks from said chamber including a driving motor, and means for varying the speed of said motor while maintaining the same in motion automatically controlled by the temperature within said combustion chamber.

20. In a blank heating furnace, a combustion chamber, means for bringing the interior of said chamber to a high temperature, means for admitting blanks to the chamber in series, means for discharging them serially including a motor continuously in motion during and in the intervals between discharge, and means controlled by the temperature in the combustion chamber for varying the supply of operating medium to said motor to control its speed and the frequency of blank discharge.

In testimony whereof I affix my signature.
CHARLES F. OSGOOD.
